UNITED STATES PATENT OFFICE.

JULES SCHWAB, OF PARIS, FRANCE, ASSIGNOR TO SOCIETE THERMOSONUS, OF PARIS, FRANCE.

AUTOMATIC FIRE-PROTECTION DOOR OR SCREEN.

Application filed June 26, 1926, Serial No. 118,868, and in France June 29, 1925.

This invention relates to automatic fire protection doors or screens. Heretofore, arrangements of this character have depended upon the melting of a fusible connection for the initiation of the closing operation intended for giving protection against the spread of fire. Such arrangements have the drawback of delayed or tardy action, so that there is risk of the fire spreading due to the fact that the flame may have passed through the opening before the closing of the door or screen.

The principal object of this invention is to remedy this defect and to provide an automatic release depending upon the action of a dilatable or expandible medium contained in a chamber liable to deformation under the dilation or expansion of the contained medium.

20 A further object is to provide a declutching mechanism adapted for being released by the deformation aforesaid and thereby permitting the door or screen to close automatically, either under its own weight or 25 under the influence of means constantly tending to move such door or screen to the closed position.

Another object of the invention is to provide means for the avoidance of any likelihood of a false operation at the wrong time due to a slow rise in temperature, this object being attained by providing the chamber with a small aperture through which leakage is permitted when expansion occurs 35 due to such slow rise of temperature.

Other objects of the invention are to provide a combination of the expansion chamber control with the fusible connection control, and to provide indicating means in connection with the said controls.

These and other objects are hereinafter fully described and explained with reference to the accompanying drawings forming part of this specification, in which drawings:—

45 Figure 1 is an elevation of a complete automatic installation of fire protection door with expandible chamber control.

50 Figure 2 is a view of a modification according to which the expandible chamber operates through the medium of a ball device.

Figure 3 is a view of an indicator device adapted for operating in conjunction with the mechanisms of this invention.

55 Figure 4 is a view illustrating the com-

bination of fusible connection and expandible chamber controls.

Referring to Figure 1, 15 is a chamber which may be deformable or which may have a deformable wall or diaphragm 17, and this chamber is provided with a small aperture or perforation at 16 for permitting of the escape of the air or gaseous medium within the chamber when expansion of such medium takes place due to a slow rise in temperature. The diaphragm or wall 17 is provided with a pip or fulcrum point 18 engaging the lever 19. The latter is pivoted to one end of a link 21, the other end of the latter being connected to one arm of a lever 22. As will appear, this lever system in the normal position in which it is shown, constitutes a locking means for preventing the door or screen 1 from moving down the inclined rail 3 to the closed position 4. The door 1 is suspended anti-frictionally by the rollers 2 running upon the rail 3. It is to be understood, however, that any other arrangement of self-closing door may be adopted, as for example one in which the door or screen descends vertically or in which the door is operated to move to the closed position by a weight or other agency constantly active upon it.

In the example illustrated, the door is connected by a cable 6 with a link or shackle 7, and the latter in the open condition of the door is engaged with a hook 36 pivoted at 37. The pull in the cable 6 tends to throw the hook 36 over in the direction of the arrow 42, but this is prevented by the stop lever 32 pivoted at 33. The lever 32 itself is held from turning by a lever 28 which is engaged by a catch or finger on the lever 22 aforesaid.

In the event of a sharp rise in temperature, such as is caused by a fire in the building, the air or gas within the chamber 15 expands quickly so that before any appreciable escape can take place through the small aperture 16 a pressure develops within the chamber 15 and the deformable wall or diaphragm 17 thereof is deformed or dilated in the outward direction thereby forcing the lever 19 outwardly. The lever 19 thus, pulls the link, 21. The engagement of the link 21 with the lever 22 causes the latter to be turned in the direction of the arrow 41 which is the direction for releasing its finger or catch from the lever 28.

The hook 36 is now free to turn in the direction of the arrow 42 under the pull of the cable as the lever 33 is no longer stopped by the lever 28 which has been released from the finger of the lever 22. Thus, the link or shackle 7 frees itself by sliding off the hook 36 and the door 1 being no longer held runs freely down to the closed position.

The hook 36 is weighted in such a manner that when it has released the link or shackle 7 and is free from the pull of the cable 6, it returns automatically to the set position seen in Figure 1. Also, the levers 32, 28 and 22 are influenced by springs 34, 30 and 25 in such a manner that they also return automatically to the set position illustrated after the release of the door. Therefore, when the alarm or the fire is over it is only necessary to open the door and re-engage the link or shackle 7 with the hook 36 in order that the mechanism may be ready for a fresh operation.

It is apparent that it is possible to devise other mechanical combinations destined to produce the closing of the screen or door 1 when the wall or diaphragm 17 is displaced. All such variants should be considered as falling within the scope of the present invention.

Another variant is represented by way of example in Figure 2.

In this figure, a plate 53, provided with a hole 54 displaces itself before an orifice 51 under the action of the membrane 17. A ball placed in the orifice 54 falls in the chimney 50 when that orifice coincides with 51. This ball causes the lever 56 to swing and, consequently, to actuate the declutching mechanism already described which liberates the link or shackle 7.

With this arrangement it is possible to combine an indicator device. For this purpose, one extremity of the lever 56 carries a bevel 65 which guides the ball towards a system of two levers in V-disposition, 68 and 69. At the extremities of the two levers are fixed indicators 66 and 67 which are displaced before a window 73. The ball in falling causes the indicator 67 to be effaced and replaces it by the indicator 66, and this gives indication to the staff that the apparatus has functioned and that the ball should be put back in place. An opening 74 permits of recovering the ball and of restoring the indicator to its initial position.

In Figure 3 there is shown a locking arrangement for this indicator. A lever 85 oscillating at 86 and pressed by a spring against the ball 55 at its position of repose actuates, by a rod, a bolt 90. When the ball 55 falls in the chimney 50, the lever 85 swings, the system takes the position in dotted lines, and the bolt 90 comes into a position such that it locks the lever device 68, 69 before the window 73.

Finally, there is represented in Figure 4 a variant in which there is combined the old system employing the fusible connector and the new system employing the expansion chamber. For this purpose, the door is maintained on the one hand by a cable 6 and a counterweight 5 (one or several fusible connectors 8, 9 being inserted in the cable 6) and, on the other hand, by a cable 110 influenced by a small counterweight 93 above which is a large weight 94. In normal times, the weight 94 exercises no pull upon the cable because it is maintained elevated by the finger or catch device 95.

The finger or catch device 95 is actuated by a release arrangement analogous to that represented in Figure 2 and controlled by an expansion chamber. The weight of the mass 5 is superior to that of the mass 93 but inferior to that of the masses 93 and 94 together. If the fire melts one or several of the fusible connectors, the screen or the door 1 descends under the combined action of its own weight and of the counterweight 93.

If, on the contrary, the fusible connectors 8 and 9 do not function immediately, the spring finger 95 is liberated by the action of the expansion chamber 15, the weight 94 operates upon a cable 110 and brings the door to its closed position.

The alarm or the fire being over, it is sufficient to raise the weight 94 above the finger 95 and eventually to replace the fusible connectors so that the arrangement may be ready for a new operation.

I claim:—

1. Arrangement for the automatic control of fire protection closure devices, comprising in combination, a fluid-containing expansible chamber, a lever mechanism directly actuated by the expansion of said chamber, a self setting detent mechanism normally operative for retaining the closure device in its open position and normally locked by said lever mechanism, said lever mechanism arranged to move the detent mechanism and to free the closure device for self-closure when the expansible chamber is deformed by a sudden expansion due to a sharp rise of temperature.

2. Arrangement for the automatic control of fire closure devices comprising in combination, a fluid-containing expansible chamber, a lever mechanism directly actuated by the movement of the said chamber when expanding, a self setting detent mechanism normally operative for retaining the closure device in its open position and normally locked by the lever mechanism, setting springs urging said mechanisms into their normal positions, a pivotal hook normally held in position controlled by gravity and by the detent mechanism, a cable hooked on said hook, urging the same to rotate on said hook, urging the same to rotate 130

- in a direction such as will cause it to be unhooked and holding the closure device in its open position, said lever mechanism arranged to move the detent mechanism and thereby free the hook and to release the closure device when the expansible chamber is subjected to a sharp rise of temperature.
3. Arrangement for the automatic control of fire protection closure devices comprising in combination a fluid containing chamber formed with a small hole for the escape of fluid in the case of slow expansion due to slow elevation of temperature and comprising a deformable wall element, a mechanism constantly tending to close said closure, a detent mechanism normally operative for retaining said closure in the open condition, locking mechanism normally locking said detent mechanism, and mechanism under control of said deformable wall and comprising a plate pierced with a hole and a ball, the said plate being movable by said wall element for releasing said ball and the latter being disposed so as to fall upon said locking mechanism to release it and permit the detent to free the closure substantially as set forth.
4. Arrangement for the automatic control of automatically closable fire protection closure devices comprising in combination a fluid-containing chamber formed with a small hole for the escape of fluid in the case of slow expansion due to slow elevation of temperature and comprising a deformable wall element, a detent mechanism normally operative for retaining said closure in the open condition, locking mechanism normally locking said detent mechanism, indicator mechanism, a transmission in connection with said deformable wall said transmission being operative for releasing said locking mechanism and means controlled by said transmission and arranged to control said indicator mechanism when said wall element is deformed by a sharp rise of temperature substantially as set forth.
5. Arrangement for the automatic control of fire protection closures comprising in combination a fluid-containing chamber formed with a small hole for the escape of fluid in the case of slow expansion due to a slow rise in temperature and comprising a deformable wall element, a counterweight mechanism and a fusible connector normally operative for retaining said closure in the open condition, a heavy weight device constantly tending to close said closure, a catch device normally restraining this latter weight from action, and a mechanical control in operative connection with the deformable wall element and adapted for liberating the catch whereby the weight is freed for closing said closure in the event of the fusible connector failing to melt in proper time.
6. Arrangement for the automatic control of fire protection closures, comprising in combination a fluid-containing expansible chamber, a counterweight mechanism and a fusible connector normally operative for retaining the closure in open condition, a comparatively small weight constantly tending to close said closure, a comparatively heavy weight adapted to fall on the small weight and to increase the closing action thereof, a catch device normally restraining the heavy weight from moving, and a mechanical control in operative connection with the expansible chamber and to free the catch, whereby the heavy and the small weights are allowed to simultaneously close the closure in the event of the fusible connector failing to melt in proper time.

JULES SCHWAB.
